UNITED STATES PATENT OFFICE.

JOSEPH J. MCKERNAN, OF PHILADELPHIA, PENNSYLVANIA.

AUTOMATIC DRAFT-REGULATOR.

No. 894,686.

Specification of Letters Patent.

Patented July 28, 1908.

Application filed October 23, 1907. Serial No. 398,808.

To all whom it may concern:

Be it known that I, JOSEPH J. MCKERNAN, a citizen of the United States of America, residing at Wissahickon, Philadelphia, in the 5 county of Philadelphia and State of Pennsylvania, have invented new and useful Improvements in Automatic Draft-Regulators, of which the following is a specification.

This invention relates to automatic draft 10 regulators, the object of the invention being to provide time trip mechanism for opening up the draft of a furnace or other heater at a predetermined time, the apparatus hereinafter described being adapted to be set so 15 as to operate at any given time.

With the above general object in view, the invention consists in the novel construction, combination and arrangement of parts hereinafter fully described, illustrated and 20 claimed.

In the accompanying drawings, Figure 1 is a view in elevation of the complete apparatus of this invention showing the same associated with the draft door of the furnace. Fig. 2 is an enlarged elevation of the 25 tripping portion of the apparatus. Fig. 3 is a sectional elevation of the support on which the tripping mechanism is mounted, looking at right angles to Fig. 2.

In carrying out the present invention, an 30 alarm clock 1 is mounted on a suitable support indicated at 2 which may conveniently consist of a closet door so that the back of the clock may be set substantially flush with the outer side of the door so that by opening 35 the door the face of the clock may be seen and the alarm mechanism of the clock set according to the time it is desired to have the draft of the furnace opened.

The furnace door indicated at 3 has attached thereto one end of a flexible draft door connection 4 which extends over suitable guide pulleys 5 and has an operating weight 6 secured thereto which weight is sufficient to effect the necessary opening of the draft door 3.

Under the preferred embodiment of the invention, the weight is provided with a ring or eye 7 through which the connection 4 is 50 passed, said connection being provided with a terminal hook 8 which may be engaged with any part of the connection so as to hold the weight 6 at any necessary elevation above the floor. At a suitable point in the 55 length of the draft door connection 4 which will ordinarily consist of a chain as shown

in Fig. 2, there is arranged a catch link 9 which is adapted to be placed over and in engagement with a stud or shoulder 10 on a weight supporting segment 11 which is pivotally mounted at 12 on the support 2, the pin or shoulder 10 being conveniently formed by providing a notch 13 in the peripheral edge of the segment 11 into which notch the catch link 9 is placed in the manner indicated in Figs. 1 and 2. The chain or connection 4 engages and passes over a pin 14 projecting from the support 2 and when the catch link 9 is placed in engagement with the segment 11 an intermediate portion of 70 the chain adjacent to said catch link is deflected to one side as shown in Fig. 2 and when the segment is held by means herein-after described a greater portion of the tension of the weight 6 on said connection 4 is 75 temporarily removed.

The segment is provided at a suitable point with a pin 15 adapted to be engaged by a hook 16 which is pivotally connected to the support 2 as indicated at 17. It is also preferred to place an anti-friction roller or sleeve around the pin 15 so as to more readily free the hook at the proper time and prevent said hook from binding on the pin 15. The hook 16 which constitutes the tripping member of 85 the apparatus is operated by means of a trip cord 18 which extends from the hook to the alarm wind arbor 19 and is wrapped around the same.

The operation of the mechanism is as follows. When the alarm wind arbor is released at a predetermined time designated on the face of the clock, the arbor 19 winds upon the trip cord 18 and draws the hook 16 out of engagement with the pin 15 thus allowing the 90 weight 6 to pull downward on the connection 4 and turn the weight supporting segment 11. When said segment has turned a sufficient distance, the catch link 9 is released from the segment and then the weight 6 acts 95 with full force on the connection 4 which being attached to the draft door 3 swings said door open and supplies the furnace with the required draft to promote combustion.

20 designates a spring connecting the 105 weight with a fixed support and acting to cushion the fall of the weight when the latter is released in the manner above described.

Having thus fully described the invention, what is claimed as new is:

An automatic draft regulator comprising 110 a hinged support, a clock embodying a rotary

arbor and mounted in an aperture in said support so that the front and back of the clock are exposed at opposite sides of the same, a weighted connection attached to the 5 draft door of a furnace, a segment pivotally mounted on the hinged support, a catch for holding said segment, a tripping connection extending from said catch to the clock arbor, and a catch link on said connection adapted

to be engaged and held by the pivoted segment.

In testimony whereof I affix my signature in presence of two witnesses.

JOSEPH J. MCKERNAN.
